UNITED STATES PATENT OFFICE.

WENDELL HESS, JR., OF TROY, NEW YORK, ASSIGNOR TO THE INTERNATIONAL MACHINERY CO., OF SAME PLACE.

STARCHING-MACHINE.

SPECIFICATION forming part of Letters Patent No. 680,774, dated August 20, 1901.

Application filed March 18, 1899. Renewed March 18, 1901. Serial No. 51,731. (No model.)

To all whom it may concern:

Be it known that I, WENDELL HESS, Jr., a citizen of the United States, residing at Troy, county of Rensselaer, and State of New York, 5 have invented certain new and useful Improvements in Starching-Machines, of which the following is a specification.

The invention relates to such improvements; and it consists of the novel construction and combination of parts hereinafter described and subsequently claimed.

Reference may be had to the accompanying drawings, and the letters of reference marked thereon, which form a part of this specification.

Similar letters refer to similar parts in the several figures.

Figure 1 of the drawings is a side elevation of my improved starching-machine. Fig. 2 is a view, partly in cross-section on the line 2 2 in Fig. 1 and partly in elevation, with the case for the charging-roll removed. Fig. 3 is a top plan view of one of the carrier-platforms detached.

25 A is the main supporting-frame of the machine, provided in its upper end with suitable supporting-bearings for the shaft A'. The shaft is provided with the driving-pulleys A², one on each end of the shaft, and on its middle portion with the charging-roll A³. The roll is inclosed, except at its lower side, by a case A⁴, into which cold laundry-starch is fed, as at the inlet A⁵, to supply the roll with starch in any known manner.

40 B is a tilting frame pivoted upon the cross-rod A⁴, which is rigidly supported by the main frame. The tilting frame supports an endless chain belt provided with a plurality of individual fabric carriers or platforms P¹, P², P³, P⁴, P⁵, P⁶, P⁷, and P⁸, adapted to be carried by the belt successively past the charging-roll, as will be more fully explained. Each one of the carrier-platforms is mounted upon a 45 pair of cross-rods B', the ends of which are each provided with a friction-roller B², adapted to travel in the trackways B³, formed on the inner sides of the oppositely-disposed sections a b of the tilting frame. The cross-rods B' 50 are connected with each other by the links B⁴ and B⁵ to form an endless belt or chain around

the tilting frame, the ends of the thicker and shorter links B⁴ being interposed between the ends of the thinner and longer links B⁵, as seen in Fig. 2. The lower sides of these links 55 are toothed to form a plate-gear adapted to mesh with the gear-wheel B⁶, fixed upon the cross-shaft B⁷, which has its bearings in the main frame. The shaft B⁷ is also provided with a fixed gear B⁸, adapted to mesh with the gear B⁹, fixed upon the hub B¹⁰, rotary on the cross-rod A⁴. The rotary hub B¹⁰ is provided with the driving-pulley B¹², fixed on the hub, all as fully shown in Fig. 2. When power is applied through the pulley B¹², the 60 endless belt or chain is caused to travel about the tilting frame, and as the toothed links pass by the gear B⁶ they come into a common horizontal plane corresponding with the horizontal position of the trackways B³ in the tilting frame, located on the upper side of the frame and just above the cross-shaft B⁷, whereby they are in the proper position to be effectively engaged by the gear B⁶, as before described. The platforms are maintained at 65 a considerable distance from their supporting cross-rods by legs P⁹. The lower ends of the legs are secured to the cross-rods and the upper ends of the legs are secured to the lower part of the platform, which is preferably a 70 metallic plate P¹⁰, as by the countersunk screw-bolts P¹². The plate P¹⁰ is covered by a rubber sheet P¹³ of considerable thickness to form a yielding embedding platform adapted to carry the goods to be starched past the 75 charging-roll. The rubber sheet is provided with the edge flanges P¹⁴, adapted to inclose and bear upon the edges of the metallic plate on all four sides.

80 My improved machine is especially adapted 90 for starching shirts, and the platform-supporting legs are curved inwardly from the ends toward the middle of the several platforms, as seen in Fig. 1, to facilitate the operation of drawing a shirt on over one end of 95 the platform, as seen at S in Fig. 1.

It is not desirable in starching a shirt to apply the starch to any part of the shirt except the bosom, neck and wrist bands, and a very small portion of the contiguous portions 100 of the shirt-body. The platforms are for this reason preferably made of a size and shape

to correspond with the size and general form of the shirt-bosoms to be starched or to the size and form commonly given to shirt-bosoms. The body part of the shirt falls below the platform or extends beyond the ends of the charging-roll and is not charged with starch. The wristbands S' are brought up over one end of the platform onto its upper surface, as seen in Fig. 1, where they are engaged and charged with starch by the charging-roll. The wristbands are held securely in place while passing the roll by the pressure of the contiguous ends of the platforms upon each other while in a horizontal position, which position they assume while passing the charging-roll.

C is a lever fulcrumed at C' upon the main frame, with its short arm bearing upon the lower side of the cross-rod C² in the tilting frame and its long arm provided with a weight C³. The weighted lever is continually pressing the rear end of the tilting frame upward, and the platforms as they successively engage the roll are thereby forced upwardly against the roll. This pressure can be varied by varying the position of the weight on the long arm of the lever.

The operation of my improved starching-machine is as follows: Power being applied to the driving-pulley, the platforms are carried around the tilting frame and successively brought into engagement with and pressed against the charging-roll, which is rapidly rotated. Each platform during each of its circuits of the tilting frame passes from the vertical position of P', Fig. 1, to the horizontal position of P² just before coming into engagement with the charging-roll and from the horizontal position of P⁴ to the vertical position of P⁵ just after leaving the roll. While the platforms are successively passing from the position of P' to that of P² an attendant at the forward end of the machine draws a shirt over the upper end of the platform and adjusts the bosom and wristbands in proper position on the platform to be engaged by the charging-roll, and while the platforms are successively passing from the position of P⁴ to that of P⁵ an attendant at the rear end of the machine removes the starched shirts from the platforms. Power is applied, through the pulleys A², to impart a high rate of peripheral speed to the charging-roll. The peripheral speed of the charging-roll is preferably several hundred times greater than the surface movement of the platforms past the roll. By forcing the platforms against the roll with a yielding pressure greater uniformity of pressure is obtained, being approximately the same on relatively thick portions as on relatively thin portions of the goods. The amount of starch inserted into the goods will depend upon the pressure between the carrier and the roll, the surplus over and above the desired amount being forced out by the pressure.

The art of starching fabrics by means of a

smooth roll driven at a high rate of speed is more fully explained in an application for United States Letters Patent filed by me October 13, 1898, and given the Serial No. 693,421.

When desired, each carrier-platform may be provided with laterally-projecting shields D, adapted to receive the body portion of the shirt, which hangs down below the platform, and protect such part from contact with other parts of the machine.

In Fig. 2 the platforms are shown provided with such shields, which are omitted from Fig. 1 for convenience of illustration.

The members a b of the tilting frame are each provided with an enlarged aperture d, through which the shaft B⁷ loosely passes, and which permit a rocking movement of the frame on its pivotal support A⁴.

What I claim as new, and desire to secure by Letters Patent, is—

1. In a starching-machine, the combination with a charging-roll, and means for imparting to the roll a comparatively high rate of peripheral speed; of an endless belt provided with a plurality of individual fabric-carriers successively coöperative with the charging-roll; and means for imparting to the belt a comparatively low rate of peripheral speed, substantially as described. 90

2. In a starching-machine, the combination with a charging-roll, having a smooth surface, and means for imparting to the roll a comparatively high rate of peripheral speed; of an endless belt having a plurality of carrier-platforms severally provided with a yielding surface and successively coöperative with the charging-roll; and means for imparting to the belt a comparatively low rate of speed, substantially as described. 100

3. In a starching-machine, the combination with a charging-roll, and means for imparting to the roll a comparatively high rate of peripheral speed; of an endless belt; a plurality of individual fabric-carriers secured to and movable with the belt and coöperative with the charging-roll; means for imparting to the belt a comparatively low rate of speed; and means for producing a yielding pressure between the roll and the several fabric-carriers, substantially as described. 110

4. In a starching-machine, the combination with a charging-roll rotary in stationary bearings; of a tilting frame; an endless belt supported by the tilting frame; a plurality of fabric-carriers secured to the belt and movable with the belt and frame into coöperative engagement, successively, with the charging-roll; and means for imparting a tilting pressure to the movable frame, whereby pressure is obtained between the carriers successively and the charging-roll, substantially as described. 120

5. In a starching-machine, the combination with a charging-roll, and means for imparting to the roll a comparatively high rate

of peripheral speed; of an endless belt having a plurality of carrier-platforms flexibly connected together and successively coöperative with the charging-roll; said platforms being 5 provided with projecting elastic end portions adapted to abut one upon another as said platforms are successively presented to the charging-roll; and means for imparting to

the belt a comparatively low rate of speed, substantially as and for the purpose set forth. 10

In testimony whereof I have hereunto set my hand this 17th day of February, 1899.

WENDELL HESS, JR.
